UNITED STATES PATENT OFFICE.

EDWARD LAAS, OF ELGIN, AND HIRAM H. SPONENBURG, OF WADSWORTH, ILLINOIS.

RAILWAY-RAIL STAY.

SPECIFICATION forming part of Letters Patent No. 703,602, dated July 1, 1902.

Application filed October 21, 1901. Serial No. 79,416. (No model.)

To all whom it may concern:

Be it known that we, EDWARD LAAS, residing at Elgin, in the county of Kane, and HIRAM H. SPONENBURG, residing at Wadsworth, 5 in the county of Lake, State of Illinois, have invented new and useful Improvements in Railway-Rail Stays, of which the following, taken in connection with the accompanying drawings, is a full, clear, and exact description.

This invention relates to devices for fastening railway-rails to their supporting cross-ties.

It is well known by persons experienced in 15 railway-track construction that the rails are caused to creep longitudinally on the cross-ties in one direction, particularly on double-track railways, owing to the constant travel of trains, which creeping movement causes 20 the rails to be moved out of alinement and the cross-ties to be shifted out of position, more especially at the rail-joints and switches.

The object of the present invention is to 25 positively anchor the rails to the ties, and thus effectually prevent such creeping of the rails and hold the cross-ties at right angles to the rails, particularly at the rail-joints, which are requirements essential to the maintenance of a perfect track construction.

30 Furthermore, the object is to provide a rail-stay which shall be simple, strong, and durable and which can be easily and conveniently applied to the track and readily removed, if required, for making repairs and which shall 35 be inexpensive in its manufacture.

To that end the invention consists in the combination, with a railway-rail and its supporting-tie, of a rail-stay comprising, essentially, a clamping-plate rigidly secured to the 40 web of the rail by a bolt passing through said parts and a depending flange bearing against the side of the tie; and the invention consists, furthermore, in other novel features of construction of the rail-stay, as hereinafter 45 fully described, and pointed out in the claims.

In the accompanying drawings, Figure 1 is 50 a side view of a portion of a railway-track, illustrating our improved rail-stay applied to a rail-joint. Fig. 2 is a vertical transverse section of the same. Fig. 3 is a plan view. Fig. 4 is a transverse section of a track-rail,

showing the rail-stay as applied intermediate the rail-joints, and Fig. 5 is a side view of a portion of a track, illustrating a modification of our invention.

55

Referring to Figs. 1, 2, and 3 of the drawings, A A represent the usual T-rails, which are fastened to the supporting cross-tie B by means of spikes a or other suitable means, according to the material of the tie, and C C 60 denote the connecting-bars or "fish-plates," which are applied to the webs b of the rails at their meeting ends and are fastened thereto by means of the usual bolts c. Said bars or plates C C may be of any suitable and 65 well-known design, but preferably formed with a base portion d, bearing on top of the rail-base e, as clearly shown in Fig. 2.

D denotes our improved rail-stay, which 70 consists of a clamping-plate f, firmly secured to the side of one of the uniting-bars C by means of one of the bolts c and formed with an inclined portion g, bearing on the base portion d of said bar, a base-plate h, extending outward from the portion g, bears on top 75 of the cross-tie B and is provided with a depending flange i, bearing against the side of the tie, said flange extending under the rail-base e and bearing with its top edge on the under side of the rail.

80 In order to allow the rail-stay to obtain a grip on the cross-tie B, so as to prevent the cross-tie from tilting or rolling, we provide the flange i with a rib or suitable projection i', which is to be forced into the side of the cross-tie, as shown in Fig. 1 of the drawings.

85 From the flange i projects at right angles a brace j, extending lengthwise the rail A and bearing against the under side thereof to guard against the breakage of the flange by 90 the strain it is subjected to in preventing creeping of the rail.

When the rail-stay is applied intermediate the rail-joints, the clamping-plate f is bolted directly to the web b of the rail, and the inclined portion g thereof bears upon the top 95 of the rail-base e, as shown in Fig. 4.

In the modification shown in Fig. 5 of the drawings the base-plate h of the rail-stay is secured to the cross-tie by spikes a' and terminates at the opposite ends with depending flanges i, bearing against opposite sides of the 100

tie B, the attaching-bolt *c* being directly over the center of said tie, and from each flange projects a brace *j*, which braces bear against the bottom of the rail-base, as hereinbefore stated.

5 It will be seen that the track-rails will be effectually prevented from creeping longitudinally on the cross-ties and the ties held securely in their proper positions.

10 It will be understood that the construction of the rail-stay may be further modified—as, for instance, the base-plate may be dispensed with, in which case the flange *i* would depend directly from the inclined portion *g* of the clamping-plate; and, still further, the flange might be omitted and the brace made to extend diagonally from the base-plate under the rail, and thus perform the function of the flange by having its forward end bearing against the side of the tie.

15 What we claim is—

20 1. The combination with the cross-tie and rail seated directly thereon, of a clamping-plate rigidly secured to the web of the rail and formed with an outwardly-extending base-plate, and a flange depending from said base-plate and bearing against the side of the cross-tie and formed with an extension bearing with its top edge on the under side of the rail as set forth.

25 2. The combination with a railway-rail and cross-tie, of a rail-stay formed in one piece

30 and comprising a clamping-plate rigidly secured to the web of the rail by a bolt passing transversely through said parts, and a brace 35 extending lengthwise the rail and bearing with one end against the cross-tie and its upper edge against the under side of the rail substantially as described.

3. The combination with the railway-rail 40 and cross-tie, of a rail-stay formed in one piece and comprising a clamping-plate bolted to the web of the rail, a depending flange bearing flatwise against the side of the cross-tie and extending under the rail-base, a projection 45 on the flange entering into the side of the cross-tie, and a brace projecting from said flange lengthwise of the rail and bearing against the under side of said rail substantially as described.

4. The combination with the rail and cross-tie, of a rail-stay formed in one piece and comprising a clamping-plate bolted to the web of the rail, a base-plate bearing on top of the cross-tie, a flange depending from the base-plate and bearing against the side of the tie, and a brace projecting at right angles from said flange and bearing against the under side of the rail substantially as described.

EDWARD LAAS.

HIRAM II. SPONENBURG.

DISCLAIMER.

703,602.—*Edward Laas*, Elgin, and *Hiram H. Sponenbury*, Wadsworth, Ill. RAIL-WAY-RAIL STAY. Patent dated July 1, 1902. Disclaimer filed April 9, 1917, by the assignee, *Otto R. Barnett*.

Enters this disclaimer—

“To that form or modification of the invention illustrated in Fig. 5 of the drawing annexed to said specification and described in said specification, namely, at line 53 to 55 of page 1 thereof, in the following words, to-wit:

“‘Fig. 5 is a side view of a portion of a track, illustrating a modification of our invention.’

“and at line 98, page 1, to line 9, page 2, in the following words, to-wit:

“‘In the modification shown in Fig. 5 of the drawings the base-plate *h* of the rail-stay is secured to the cross-tie by spikes *a'* and terminates at the opposite ends with depending flanges *i*, bearing against opposite sides of the tie *B*, the attaching-bolt *c* being directly over the center of said tie, and from each flange projects a brace *j*, which braces bear against the bottom of the rail-base, as hereinbefore stated.

“‘It will be seen that the track-rails will be effectually prevented from creeping longitudinally on the cross-ties and the ties held securely in their proper positions.’
